Primary Examiner — Darlington Ly*(74) Attorney, Agent, or Firm* — Drinker Biddle & Reath LLP(57) **CLAIM**

The ornamental design for a round lock for a bag, as shown and described.

DESCRIPTION

1. Round lock for a bag

1.1 is a front perspective view of an round lock for a bag showing my new design;

1.2 is a front elevation view thereof;

1.3 is a rear elevation view thereof;

1.4 is a left side elevation view thereof;

1.5 is a right side elevation view thereof;

1.6 is a top plan view thereof;

1.7 is a bottom plan view thereof; and

1.8 is a front perspective view thereof, wherein the round lock is shown on an exemplary bag.

A two-piece round ornamental lock for securing a flap on a bag, such as a handbag or clutch; the handbag shown in broken lines in 1.8 is provided for the purposes of illustrating environmental structure and forms no part of the claimed design.
